UNITED STATES PATENT OFFICE.

GEORGE L. CURLE, OF MINNEAPOLIS, MINNESOTA.

MEANS FOR CASTING ITALIC TYPE.

1,427,363.

Specification of Letters Patent. Patented Aug. 29, 1922.

Application filed April 7, 1920. Serial No. 371,999.

To all whom it may concern:

Be it known that I, GEORGE L. CURLE, a citizen of the United States, residing at Minneapolis, in the county of Hennepin and State of Minnesota, have invented certain new and useful Improvements in Means for Casting Italic Type; and I do hereby declare the following to be a full, clear, and exact description of the invention, such as will enable others skilled in the art to which it appertains to make and use the same.

My invention relates to machines for casting linotypes and is directed to improved means for casting italics by automatic or machine actions.

The invention is applied generally to linotype casting machines, but in the drawings is illustrated as applied to a linotype casting machine of well known commercial Mergenthaler type, and in the following specification, the invention will be described as applied to such machine.

In a line of properly assembled italics, portions of the letters should overhang portions of adjacent letters, and this should be done without providing the matrices with type faces that project beyond the sides of the matrices. Hand type have been provided with overhanging lateral projections, but these are objectionable even in hand type because they are liable to be broken off, and moreover, matrices with such projections could not be used in an automatic machine. Good italics cannot be cast from matrices assembled at right angle across the face of the mold, because with such assemblage of the matrices it is impossible to get an overhanging of certain of the characters in respect to adjacent characters.

I avoid the above noted objectionable features and obtain with an automatic machine, perfect italics, by a novel scheme and arrangement which, briefly outlined, is as follows:

The italic characters on the matrices have their major axes extended parallel to the sides of the matrices and have their minor portions oblique to the sides of the matrix. These matrices are then assembled at the mold on lines that are oblique to the face of the mold, with the minor axes of the characters extended parallel to the longitudinal axis of the mold and with all of the assembled italic characters properly aligned in respect to the mold. With this arrange-

ment, therefore, the italic characters cast on the linotype slug will be closely assembled, perfectly spaced and with portions of certain of the italic characters overhanging portions of certain other of the italic characters. To illustrate this latter feature, in the word "Fourth", for example, the top of the capital letter "F" will overhang a portion of the adjacent letter "o". Further illustrations might be given, but the above will suffice for the present.

In the application of my invention to a linotype machine of the Mergenthaler type, for example, the first important modification thereof is to provide the vise jaws with matrix clamping faces that are oblique to the longitudinal axis of the mold, so that the line of matrices assembled between the jaws at the mold will be set as above stated.

The above modification of the vise jaws makes necessary or very desirable other highly important changes, such for example, as a modification of the construction of the space band justification bar, so that the space bands, which, in the above stated manner of assembling of the matrices, will be also set oblique to the mold, will, when pushed to place, be driven by a force applied parallel to the major axes of said space bands, so as to prevent banding of the latter. Other minor but important features of novelty will also appear in the following description.

In the accompanying drawings which illustrate the invention, like characters indicate like parts throughout the several views.

Referring to the drawings:

Fig. 1 is a fragmentary view chiefly in elevation looking away from the walls, showing the first elevator head, the vise jaws, the space band justification bar and certain other parts which particularly co-operate in the application of my invention;

Fig. 2 is an elevation looking at the face of the mold wheel and showing also the mold with some parts being broken away;

Fig. 3 is a fragmentary view showing the two vise jaws which, in said view, however, are adjusted for Roman characters;

Fig. 4 is a fragmentary section taken parallel to the side face and approximately at the transverse center of the left hand jaw shown in Fig. 3;

Fig. 5 is a view corresponding to Fig. 1, but showing the space band justification bar

raised, and the first elevator dropped to position and matrices between the jaws of the vise.

Here it may be stated that Figs. 2 and 5, if placed face to face, would bring the mold into position for the casting of characters on the assembled matrices;

Fig. 6 is a fragmentary view with some parts sectioned on the line 6—6 of Fig. 1, 10 but with some parts shown in full and with the supplemental space band justification bar turned into inoperative position;

Fig. 7 is a vertical section taken approximately on the line 7—7 of Figs. 2 and 5, 15 with the parts shown in said Figs. 2 and 5 brought into co-operative position for casting;

Fig. 8 is a fragmentary view taken approximately on the line 8—8 of Fig. 5;

20 Fig. 9 is a face elevation of one of the matrices having an italic character thereon designed in accordance with my invention;

Fig. 10 is a face elevation of a linotype slug cast in accordance with my invention, 25 the position of the matrices in which the characters were cast being indicated by dotted lines;

Fig. 11 indicates a line printed from the slug shown in Fig. 10, the outline of the 30 slug being indicated by dotted lines;

Fig. 12 shows assembled italic matrices; and

Fig. 13 shows assembled Roman matrices.

The construction and operation of the 35 commercial Mergenthaler linotype machine is well known, and hence, those portions thereof that perform the customary functions and which have relation particularly to my invention, may be briefly described as 40 follows:

The mold, which, except as presently noted, is of the customary construction, is indicated, as an entirety, by the numeral 12 and the mold wheel which carries this mold in the usual way is indicated by the numeral 45 13. The numeral 14 indicates a portion of the crucible wall and the numeral 15 the mouth piece thereof, with which the mold is adapted to be aligned in the well known 50 manner by movements of the mold wheel. The mold 12 is, as is well known, provided with movable right and left sheet liners 12^a which are of the customary construction except that in italics, their ends are made 55 oblique to correspond to the angle or tilt given to the italic matrices when assembled at the mold.

The numeral 16 indicates the so-called 60 first elevator which is provided with the customary head 17 with guide channel for the matrices 18 and justification bands 19. The well known function of this so-called first elevator is to carry the assembled line of matrices to and from the mold, and to 65 and from position between the vise jaws.

The said vise jaws are indicated by the numerals 20 and 21, the face of which, as already stated, are in accordance with my invention, made oblique to the longitudinal axis of the mold and, as will presently more 70 fully appear. The vise jaw 21, as is usual, will be adjustable in respect to the vise jaw 20, so as to obtain the line length desired. It may be further stated that the vise jaws 20 and 21 are carried in the customary way 75 on the vise head 22.

The space band justification bar, as shown, is of the customary Mergenthaler type, being made up of two parts 23 and 24 connected by dowel pins 25, said bar 23 being directly carried on the upper ends of vertical flanges 26 operated in the well known manner.

Before describing in detail the illustrated arrangement of my invention, attention is 80 called to the manner in which the characters are applied on the matrices, attention being directed preferable to Fig. 9, wherein it will be noted that the capital letter "F" there illustrated, has its horizontal portions 85 formed oblique to the sides of the matrix 18, as stated in the introductory part of this specification. Also, it will be noted that the channels 18^a in which the characters are 90 formed are oblique to the sides of the matrix. Moreover, it should be noted that the upper and lower edges of the ears 18^b and 18^c of the matrices are parallel to the edges 95 of the character channels 18^a and hence, oblique to the sides of the matrix, this being, as will hereinafter more clearly appear, to permit the matrices to freely swing in the guide channel of the first elevator into position oblique to the mold.

These oblique edges on the said matrix 105 ears also provide for proper alignment of the characters of the matrices, regardless of varying widths of the matrices.

The matrix engaging face of the vise jaws, as stated, are oblique. They might be 110 made permanently oblique, but inasmuch as it is desirable to make the jaws readily convertible for use either with italics or with Roman characters, I provide an extremely simple means for converting the jaws from 115 the one purpose to the other. This vise jaw construction is best illustrated in Figs. 1 and 3. by reference to which it will be noted that the jaws proper are formed with oblique surfaces 27 and vertical surfaces 28 formed, respectively, with dove-tailed grooves 27^a and 28^a, and wedge shaped jaw clips 29 are provided with dove-tailed ribs 120 for engagement, at will, with either of the said grooves 27^a or 28^a. Fig. 1 shows the 125 jaw clips applied so as to make the complete matrix faces of the jaws 20 and 21, oblique to the longitudinal axis of the mold and parallel to each other, while Fig. 3 shows the clips applied so as to make the 130

engaging face of the jaws vertical and at right angle to the longitudinal axis of the mold.

To hold the jaw clips 29 in working position, spring pressed lock pins 30 are inserted therein, as shown in Fig. 4, in the vise jaws adjacent to each of the channels 27^a and 28^a, and the ends of these pins are adapted to engage notches in the edges of 10 the ribs of the vise clips 29, and the ends of these pins are adapted to engage spaced notches or depressions formed in the sides of the channels 27^a and 28^a.

To provide, as already generally stated, 15 for proper driving of the space bands to working positions, the space band justification bar is provided with a serrated driving surface 31; and preferably, this serrated driving surface is formed directly on a de- 20 tachable supplemental bar 32, having at one edge, projecting ears that are connected at 33 to ears of oblique guide bolts 34 mounted to slide in oblique guide sleeves 35 rigidly secured to a supporting plate 36 (see par- 25 ticularly Figs. 5 and 7), the upper edge of which is rigidly secured to the lower portion of the vise head 22.

Summary of operation.

- 30 The italic matrices are assembled in the assembler box, not shown, and transferred therefrom to the so-called first elevator in the usual way and by the said first elevator, are lowered between the vise jaws in the cus- 35 tomary way, except, that as they are lowered together with whatever space bands may be assembled therewith, will be tilted to oblique positions by the oblique face of the jaws. This tilting of the matrices and 40 justification bands aligns the matrix characters with the mold with the italic characters overhanging, as already stated. The assembled line, upon being dropped between the vise jaws will, of course, hang quite 45 loosely at first, but will be justified when the space bands are forced upward. The forcing upward of the space bands is produced by the customary upward movements of the space band justification bar 23. With this 50 improved and modified arrangement of the said space band justification bar, however, the ratchet-like teeth or oblique driving surfaces 31 of the supplemental bar 32 will engage the lower ends of the space bands; and 55 here it is important to note that the driving surfaces of the said serrations 31 that engage the lower ends of the justification bands standing at right angles to the major axis of said bands. The justification bar 23, 60 it will be noted, is given true vertical movement, while the supplemental driving bar 32, as it is moved upward, is guided by the oblique bolts 34 which work in the oblique guide sleeves 35 and extend parallel to the 65 obliquely set space bands, so that under said

driving movement, the supplemental bar 32 will be caused to move toward the right, in respect to Fig. 5, thereby maintaining the initial contact between the lower ends of space bands and serrated driving surfaces 70 and applying the driving force to the space bands in the direction of their longitudinal axes. This driving action is important, because it prevents breaking of the space bands. Attention is further called to the 75 fact that the ratchet-like serrations 31, while they positively prevent the lower ends of the space bands from moving toward the right, in respect to Fig. 5, after once being engaged therewith, do not prevent the said 80 bands from slipping toward the left from one to an adjacent oblique driving surface. This is also important because, when the space bands and matrices are first deposited between the jaws, they will be loosely held 85 and will not be moved to their final oblique positions until the justification of the line has been nearly completed. This justification of the line, as is well known, is, in the Mergenthaler machine, produced by a 90 progressive repetition of upward movements of the justification bar. The above noted arrangement of the driving surfaces there- 95 for permits the space bands to shift slightly and properly arrange themselves for final justification of the line.

By reference to Fig. 5, which shows the justified line assembled in position for casting, it will be noted that the oblique character channels 18^a of the matrices are in 100 true alignment and that they extend parallel to the mouth of the mold, while the characters of the matrices are oblique and in the overhanging arrangement already noted, and which arrangement is essential 105 to the production of good italic characters.

Of course, the re-distribution of the matrices after casting, is, or may be, as usual in Mergenthaler or other machines of that character and need not be here further con- 110 sidered.

To convert the machine for the customary use it is only necessary to turn the supplemental bar 32 into an inoperative position, as shown in Fig. 6; to re-adjust the jaw 115 clips 29, to position shown in Fig. 3; which adjustment, Fig. 3, again provides the jaws with vertical faces or with faces at right angles to the longitudinal axes of the mold; to substitute for the oblique end liners 12^a, 120 other liners having the customary right angle ends; and, of course, to substitute matrices having Roman characters.

By reference to Fig. 10, it will be noted that the italic slug *y*, as there shown, has 125 oblique ends, the oblique ends being parallel to the obliquely set matrices. The purpose of this is to permit two or more slugs to be set end to end, while, at the same time, measured to proper spacing between oblique 130

end characters of the slugs. If it were not desirable to thus arrange for the proper setting of the slugs into the end, the customary mold liners having right angle ends, might 5 be employed even in the casting of italic slugs. Obviously, a machine having my invention incorporated therein, as described, may be very quickly and easily converted, whether in the cast of italics or in the horizontal work.

What I claim is:

1. In a linotype machine, the combination with a mold, of vise jaws associated with the mold and having matrix engaging faces 15 that are oblique to the mold, and a space band justification bar having a supplemental shifting section formed with serrated driving surfaces that are at a right angle to the oblique faces of the said jaws, and an oblique 20 bar shifting guide operative on said supplemental bar section to cause the same to move on a line parallel to the oblique faces of said jaws, in the line justifying action.
2. In a linotype machine, the combination 25 with a mold, of vise jaws associated with the mold and having matrix engaging faces that are oblique to the mold, a space band justification bar having a supplemental shifting section formed with serrated driving surfaces that are at a right angle to the oblique 30 faces of the said jaws, and an oblique bar

shifting guide operative on said supplemental bar section to cause the same to move on a line parallel to the oblique faces of said jaws in the line justification action, the 35 said supplemental bar section being movable to and from operative position.

3. In a linotype machine, the combination with a mold, of vise jaws associated with the mold and having matrix engaging faces 40 that are oblique to the mold, a space band justification bar having a supplemental shifting section formed with serrated driving surfaces that are at a right angle to the oblique 45 faces of the said jaws, and an oblique bar shifting guide operative on said supplemental bar section to cause the same to move on a line parallel to the oblique faces of said jaws, in the line justifying action, said supplemental bar being hinged to its oblique 50 guides for movements to and from an operative position on the main justification bar.

4. In a linotype machine, vise jaws provided with vertical and oblique surfaces and with wedge-shaped jaw clips, the said jaw 55 clips being shiftable from one position in which they form the jaws with vertical matrix engaging faces, into positions in which they form said jaws with oblique matrix engaging faces.

In testimony whereof I affix my signature.

GEORGE L. CURLE.
